CLAIM

The ornamental design for an electronics housing for a flowmeter, as shown and described.

DESCRIPTION

FIG. 1 depicts a perspective view of an electronics housing; FIG. 2 depicts a front view thereof; FIG. 3 depicts a back view thereof; FIG. 4 depicts a right view thereof; FIG. 5 depicts a left view thereof; FIG. 6 depicts a top view thereof; FIG. 7 depicts a bottom view thereof; and, FIG. 8 depicts a cross-sectional view taken across line 8-8, as shown in FIG. 6.

The oblique shade lines in the Figures indicate transparent or translucent surfaces and not surface ornamentation. The broken lines in the drawings illustrate features of the electronics housing for a flowmeter that form no part of the claimed design.
